DESIGN FOR A CHAFING-DISH AND STAND.

No. 39,695.

Specification for Design.

Patented Dec. 22, 1908.

Application filed May 4, 1907. Serial No. 371,934. Term of patent 7 years.

To all whom it may concern:

Be it known that we, LIONEL STRASSBURGER, a citizen of the United States, and CHARLES NELSON, a subject of the King of Sweden, both residing in the borough of Brooklyn, county of Kings, and State of New York, have invented a new and ornamental Design for a Chafing-Dish and Stand, of which the following is a specification, reference being had to the accompanying drawing, forming a part thereof.

In the drawing we have shown the design in perspective.

The design comprises a chafing dish and stand, in which the stand has square legs, the fronts thereof having different characteristics from the back, which is indicated in the drawing by the shaded and unshaded portions respectively. The dish

support is square, and projecting square protuberances are at the corners thereof in line with the upper ends of the legs. The brackets for the side handles are rectangular, and the side handles themselves are square. The support for the top knob is rectangular, and the knob itself is square in shape. The main handle of the dish is of square cross section. The lamp support is square and is connected to the legs by single braces.

We claim:

The ornamental design for chafing dish and stand as shown and described.

LIONEL STRASSBURGER.
CHARLES NELSON.
